UNITED STATES PATENT OFFICE

138,045

DESIGN FOR A HELICOPTER

Igor I. Sikorsky, Long Hill, Conn., assignor to United Aircraft Corporation, East Hartford, Conn., a corporation of Delaware

Application December 26, 1942, Serial No. 109,143

Term of patent 7 years

(Cl. D71—1)

To all whom it may concern:

Be it known that I, Igor I. Sikorsky, a citizen of the United States, residing at 5814 Main Street, Long Hill, Bridgeport, in the county of Fairfield and State of Connecticut, have invented a new,
original, and ornamental Design for Helicopter, of which the following is a specification, reference being had to the accompanying drawing, forming part thereof.

Fig. 1 is a top perspective view of a helicopter
showing my new design;

Fig. 2 is a side elevational view;

Fig. 3 is a top plan view; and

Fig. 4 is a front elevational view.

I claim:

The ornamental design for a helicopter, as shown.

IGOR I. SIKORSKY.
